[57] **CLAIM**

The ornamental design for an indexable vertical bookshelf for oversized books, as shown and described.

DESCRIPTION

FIG. 1 is a top plan view of an indexable vertical bookshelf embodying my new design;

FIG. 2 is a right side view thereof, the left side being a mirror image of the side shown;

FIG. 3 is a front side view thereof;

FIG. 4 is a back side view thereof;

FIG. 5 is a bottom plan view thereof utilizing caster wheels;

FIG. 6 is an alternative bottom view thereof utilizing adjustable guides;

FIG. 7 is an exploded perspective view showing all of the components of the indexable vertical bookshelf, including, a cabinet module, a card index module having a removable indexing drawer, and a top module (the woodgrain has been omitted from this view to better show the structural appearance of the design);

FIG. 8 is a front side view of the indexable vertical bookshelf without the index drawer; and,

FIG. 9 is an enlarged partial perspective view of the top left front corner of the cabinet module of the indexable vertical bookshelf showing the detail of a recessed lable holder.

FIGS. 7 and 9 are provided for convenience of illustration.
